UNITED STATES PATENT OFFICE.

WILLIAM F. ZABRISKIE, OF DETROIT, MICHIGAN, ASSIGNOR TO GABRIEL STEEL COMPANY, OF DETROIT, MICHIGAN, A CORPORATION OF MICHIGAN.

DAMPER OPERATING MECHANISM.

Application filed July 27, 1925. Serial No. 46,389.

The invention relates to dampers of the type usually employed in controlling flues of open fireplaces and the invention consists in the novel construction of operating mechanism therefor as hereinafter set forth.

In the drawings;

Figure 1 is a vertical longitudinal section through a portion of the chimney flue showing my improved damper in relation thereto. Figure 2 is a perspective view of the damper operating mechanism.

Figure 3 is an elevation showing a slightly modified construction.

Figure 4 is a view similar to Figure 1 showing the parts in a different position of adjustment.

A is a chimney flue of the usual construction and B is the damper frame or box which is set into this flue. This box is preferably formed of sheet metal having an oblique front wall C fitting beneath the masonry and terminating in the upwardly extending flange D and downwardly extending flange E. The rear wall F is less in height being provided with the laterally extending flange G set in the masonry and having pivotally secured adjacent to its upper edge the damper H. This damper sits against the inclined side flanges of the box and when resting thereon completely closes the throat of the flue.

To form an operating mechanism for this damper which is positive in its operation both in opening and closing and which is simple and inexpensive to manufacture, I have devised the following construction;

I is a section of metal tubing of a length to extend between the front wall C and rear wall F of the damper box. J is a short stub shaft fitting within the end of the tube I and attached thereto preferably by electric welding. K is a segmental cam plate which may be formed of a sheet metal stamping being provided with an aperture for sleeving the same on the tube I and with a cam slot L eccentric to said tube. The inner side of this cam slot is formed with a series of notches M for successively engaging a laterally projecting pin N on the damper H. This pin is riveted or otherwise secured to the damper and extends in the axial plane of the tube I so that in the rotation of said tube the damper may be either raised or lowered; also the notches M form resting

points for holding the damper in various positions of adjustment.

To assemble the operating mechanism with the damper and frame B, the stop shaft J is inserted in an aperture in the inner wall F while the outer end of the tube is registered with a corresponding aperture in the oblique wall C. The rod O is then inserted through an aperture in the masonry which is lined with the tubular bushing P the inner end of said rod telescopically engaging the tube and being secured by a set screw Q. This set screw engages a threaded bearing formed by a nut R which is preferably electrically welded to the tube. By reason of this telescopic engagement between the rod O and tube I variations in the thickness of the masonry wall may be compensated for without change in position of the operating handle at the outer end of the rod. This handle S is welded or otherwise secured to the rod and when the said screw Q is tightened, will be secured from displacement.

My construction described accomplishes in a very simple manner functions which are usually performed by a much more complex structure. It will be noted that there are no castings or forged parts and that all of the elements are simple in construction and easily assembled.

For some installations it is preferred to dispense with the operating handle and to provide means for adjusting the damper by a poker or similar tool. Thus, as shown in Figure 3, the plate K has attached thereto on one side of the shaft, a ring T through which the end of the poker may be inserted. This will enable the operator to adjust the damper by either drawing down or pressing upward on this ring and thereby rotatably adjusting the plate. With such constructions the rod O and handle S are dispensed with and a short stub shaft such as J is used at the forward end of the tube I.

What I claim as my invention is:

1. The combination with a damper frame and a damper hinged thereto, of an operating mechanism for said damper comprising a tube extending between the front and rear walls of the damper frame, rods engaging the opposite ends of said tube and extending through apertures in said front and rear walls to form journals therefor, one of

said rods being provided with an actuating handle, a sheet metal cam plate mounted upon and secured to said tube and a pin secured to said damper and extending into operative relation to said cam plate.

2. The combination with a damper frame or box and a damper hinged thereto, of an operating mechanism for said damper comprising a tube extending between the front and rear walls of said frame, a pin inserted in and secured to the rear end of said tube and having a projected portion engaging an aperture in the rear wall of said damper box, a rod passing through the forward wall 10 of said damper box and telescopically engaging said tube, the forward end of said rod being provided with a handle, a set screw for adjustably securing said rod to said tube, a sheet metal cam plate having 15 an eccentric cam slot notched on its under side, and a pin extending laterally from said damper in the vertical plane of said tube, said pin engaging said cam slot and being held in various positions of adjustment 20 by the notched face of said slot.

3. The combination with a damper frame or box and a damper hinged thereto, of an operating mechanism therefor comprising a tube extending between the front and rear walls of said box, a sheet metal cam plate sleeved on said tube and a pin inserted in the rear end of said tube each being secured by welding, said cam plate being provided with an eccentric cam slot notched on its 30 under face, a pin secured to said damper and projecting laterally therefrom in the vertical plane of said tube and extending through said cam slot, a rod telescopically engaging said tube and together with the pin 35 at the opposite end of said tube forming journal bearings in the front and rear walls of the box, said journal bearings forming journals in the front and rear wall of the box, a handle at the outer end of said rod and a 40 set screw on said tube for securing said rod thereto.

4. The combination with a frame or box having a vertically rear wall and an ob-

liquely inclined front wall, of a damper hinged to the rear wall of said box and a 50 damper operating mechanism comprising a tube extending between the front and rear walls of said box and being provided at its rear end with a telescopically engaged pin 55 secured thereto and forming a journal in said rear wall, an operating rod inserted through the masonry and an aperture in said forward wall to telescopically engage said tube, a set screw for securing said tube to said rod, a sheet metal cam apertured to the sleeve 60 on said rod and welded thereto, said plate having an eccentric cam groove notched on its under face, and a pin secured to said damper and projecting laterally therefrom in the vertical plane of said tube, said pin 65 passing through said cam slot and being adjustably secured by the notched bearings of said slot.

5. The combination with a damper frame and a damper hinged thereto, of an operative 70 mechanism for said damper comprising a tube extending between the front and rear walls of the damper frame, rods engaging the opposite ends of said tube and extending through apertures in said front and rear 75 walls to form journals therefor, a sheet metal cam plate mounted upon and secured to said tube, a pin secured to said damper and extending into operative relation to said cam and a ring secured to said cam plate on one side of said tube for engagement of a poker or other tool to operate the same.

6. The combination with a damper frame and a damper hinged thereto, of an operating member extending in a direction transverse to the axis of the hinge, a cam member mounted on said rotary member in a plane perpendicular to the axis thereof, said cam member having a cam slot eccentric to the axis and a pin projecting transversely from 80 said damper and engaging said cam slot whereby the rotation of said operating member will positively actuate said damper body in opening and closing the same.

In testimony whereof I affix my signature.

WILLIAM F. ZABRISKIE.
